(57) **CLAIM**

The ornamental design for a lacrosse head shield, as shown and described.

DESCRIPTION

FIG. 1 is a front perspective, exploded view of a lacrosse head shield;

FIG. 2 is a front perspective view of the embodiment shown in FIG. 1;

FIG. 3 is an end view of FIG. 1;

FIG. 4 is top view of FIG. 1;

FIG. 5 is a side view of FIG. 1;

FIG. 6 is an opposite view of FIG. 4;

FIG. 7 is an opposite side view of FIG. 5; and,

FIG. 8 is an opposite view of FIG. 3.

The broken lines used in FIGS. 1 and 2 of the drawings disclosure are for illustrative purposes only and form no part of the claimed design.
